CHILLING APPARATUS

Nicolai H. Hiller, Carbondale, Pa., assignor, by
mesne assignments, to Worthington Pump and
Machinery Corporation, Harrison, N. J., a cor-
poration of Virginia

Application October 31, 1933, Serial No. 695,988

14 Claims. (Cl. 62—126)

The invention in its preferred form is an improvement in chilling apparatus of the general heat interchanger type shown in the Hiller Patent No. 922,898, and adapted for the treatment 5 of liquids to effect congealation and separation therefrom of certain solid constituents. Such an apparatus, for instance, is adapted for use in the chilling of distillates to separate paraffine, wax or the like. The present invention, in certain 10 of its broader aspects, may be utilized in other types of heat interchangers as well as in the type of chilling apparatus above referred to.

It has been proposed to provide a heat inter- 15 changer comprising one or more vertical series of pipes to which a volatile refrigerant is de- 20 livered by gravity from an accumulator disposed above the level of these pipes. In such ex- 25 changers, there is a substantial back pressure on the refrigerant liquid, which varies in ac- 30 cordance with the static liquid head of the vola- 35 tile refrigerant, and which affects the ebullition temperature thereof.

One object of the present invention is to pro- 20 vide a chilling apparatus having improved means 25 whereby the back pressure, due to the liquid head of the volatile refrigerant, is substantially the same in each of the series of evaporator sec- 30 tions disposed at different elevations.

Still another object is to provide an evaporator 30 system having a plurality of passages for the refrigerant arranged in parallel, and having means for insuring the even distribution of re- 35 frigerant to said passages.

Another object is to provide new and im- 35 proved means for preventing leakage in the chilling apparatus.

In my improved apparatus, I provide a plu- 40 rality of pipe sections disposed at different levels for conducting the liquid to be treated, and a corresponding plurality of evaporator sections 45 connected in parallel and respectively disposed in heat exchange relationship with said pipe sec- 50 tions to chill the liquid therein.

As one feature of my invention, I separately 45 deliver refrigerant liquid and separately take off refrigerant gas from the separate sections at different elevations.

As another feature, the connections between 50 the pipes of each evaporator section are connected in series at the tops of the pipes to insure against the trapping of superheated gases in the evaporator system.

As still another feature, I provide a circulating 55 pump for circulating the refrigerant agent through the evaporator sections, and a metering

device at the inlet to each section to effect even distribution of refrigerant to each of said sec- 5 tions. The circulating pump serves not only to keep all the evaporator sections full of refrigerant, but also increases the circulation. This forced circulation increases the value of the co- 10 effient of heat transmission.

As a further feature, the circulating pump is disposed below a surge drum or accumulator to insure keeping the pump flooded and to prevent 15 the circulating pump from being gas bound.

In the accompanying drawings, there is shown for the purpose of illustration, one embodiment of the present invention. In these drawings:

Fig. 1 is a perspective view of an apparatus 15 embodying the present invention.

Fig. 2 is a section taken on the line 2—2 of Fig. 1.

Fig. 3 is a top plan view, partly in section, of a portion of the apparatus shown in Fig. 1. 20

Fig. 4 is a section showing details of a stuffing 25 box for the scraper shaft.

Fig. 5 is a section taken on the line 5—5 of Fig. 3.

Fig. 6 is a section showing details of a portion 25 of Fig. 3, but somewhat enlarged, and

Fig. 7 is a section showing a portion of the 30 apparatus of Fig. 2, but somewhat enlarged.

In the construction illustrated, there are pro- 35 vided three horizontal coils or connected pipe sections A, B and C disposed in superposed relationship and each comprising a plurality of pipes 10 serving to conduct the liquid to be treated. Concentrically mounted with respect to said pipes 10 are pipes 11 forming annular chambers there- 40 with for the passage of a chilling agent. Ad-joining pipes 10 of each section are connected together in series at one end by horizontal bends 12 and at the opposite end by horizontal bends 13 arranged in staggered relationship with re- 45 spect to the bends 12, whereby all of the pipes 10 of each section are connected together in series.

The upper horizontal pipe section A is connected in series with the lower pipe section B by 45 means of a vertical bend 14 connecting the vertically adjoining end pipes 10 of the two sections, and the pipe section B is similarly connected in series with the section C by a vertical bend 15. End pipes 10 of the sections A and C are provided 50 respectively with an inlet 16 and an outlet 17 so that liquid to be treated flows into the inlet 16 and successively through the three sections. This particular arrangement of pipe sections is not 55 important as various other arrangements may be

employed as to the number of sections at different elevations and the number of pipes in each section, and all of the pipes may be connected in a single series or in two or more series in parallel.

- 5 For scraping the congealed portions of the liquid from the inner surface of the pipe 10, the bends 12, 13, 14, and 15 have journaled therein shafts 18 which extend axially of the pipes 10, and which carry spiral, screw or ribbon conveyors 19
 10 having the outer peripheries thereof close to the inside surface of said pipes. These may be of the type shown in the Torrance Patent No. 1,796,772, issued March 17, 1931.

The shafts 18 may be rotated by any suitable means. Merely as an example I have shown sprocket wheels 20 connected to one set of shaft ends, and engaged by one or more chains (not shown) disposed in zig-zag relationship between vertically adjoining wheels, the chain or chains 20 being driven from any suitable source of power.

As a feature of the present invention, the pipes 11 form a plurality of evaporator sections connected in parallel and respectively disposed in heat exchange relationship with the pipe sections A, B and C. For that purpose, there are provided pipes 21 connecting the ends of horizontally adjoining pipes 11, and arranged in staggered relationship to connect the pipes 11 of each section together in series. The volatile refrigerant is introduced into each evaporator section by means of an inlet pipe 22 connected to an end pipe 11 of each of said sections and extending from a vertical inlet header 23. The opposite end pipe of each evaporator section is provided 35 with an outlet pipe 24 connected to a vertical return header 25. By means of this arrangement, while the liquid to be treated flows successively downwardly through the three pipe sections A, B, and C, and the volatile refrigerant is delivered 40 from the inlet header 23 and horizontally through the three separate evaporator sections, so that each pipe section is chilled by a different batch of volatile refrigerant.

As an important feature of the present invention, the pipes 21 and 24 forming the outlets of the pipes 11 are connected to the tops of said pipes 11, while the inlet pipes 22 are connected to the bottoms of said pipes 11 to insure against 50 the trapping of superheated gases in the evaporator sections, thereby preventing the cutting down of chilling surface.

The bottom of the return header 25 is connected to the top of a surge drum or accumulator 55 26 disposed below the level of the lowest evaporator section. By means of this arrangement, the returns from all the outlets of the three evaporator sections have free vents, the gas and liquid refrigerant falling into the accumulator 26 60 and thus preventing any back pressure due to liquid head.

As a feature of the present invention, the volatile refrigerant is circulated through the three evaporator sections by means of a pump 27 which 65 may be of any suitable type, and which, in the form shown, consists of a rotary pump driven from any suitable source of power such as a motor 28. The refrigerant is delivered from the drum 26 to the suction side of the pump 27 by means of a connection 29 connected to the bottom of the drum, said pump being disposed below the surge drum to insure keeping the pump flooded and to prevent it from being gas-bound. 70
 75 The discharge side of the pump 27 is connected

to the bottom of the inlet header 23 by means of a pipe connection 30.

The drum 26 is provided with an inlet pipe 32 leading from a condenser or other source of liquid refrigerant, this inlet being controlled by means of a valve actuated by a float 33 so as to maintain the level of liquid refrigerant in the drum 26 constant. Also connected to the top of the drum 26 is an outlet pipe 34 for returning the gases to a compressor or other suitable part of the 10 refrigerating system.

As an important feature of the present invention, the amount of liquid that is delivered to each evaporator section is controlled by means of a metering device in the form of an orifice 15 plate 35 (see Fig. 7) disposed in each of the inlet pipes 22. In the form shown, each inlet pipe 22 is formed of two sections 36 and 37 coupled together at their ends, the section 36 having at its coupled end the orifice plate 35. By means of this arrangement, the even distribution of volatile refrigerant to each of the evaporator sections is assured, and the liquid pressure at the discharge side of each orifice plate may be the same regardless of differences in the elevation thereof. 20
 25

The outer pipes 11 are sealed around the pipes 10 to prevent leakage of the volatile refrigerant. For that purpose, the pipes 11 at one end may be welded circumferentially to the inner pipes 10, while at the other end they are provided with 30 stuffing boxes 40 (see Fig. 6). Each stuffing box 40 includes a metal ring 41 welded or otherwise secured to the inner surface of each pipe 11, and having a central opening large enough to permit easy slippage of the pipe 10 therein. Abutting 35 the ring 41 is a metal washer 42 closely embracing the outside of the pipe 10. Also encircling the pipe 10 is a gland 43 having a cylindrical hub 44 adapted to slide axially in the interior of the pipe 11. Disposed between the inner end of 40 the hub 44 and the washer 42 are a number of packing rings 45. The gland 43 is forced axially inwardly in the interior of the pipe 11 by means of bolts (not shown) passing through an outwardly extending flange 47 of the gland 43, and 45 a collar 47a welded or otherwise secured on the outside of the pipe 11.

Each scraper shaft 18 on the driven end thereof is journaled in a bearing bracket 48 connected to a bend 12. The bracket 48 includes a bearing 50 supporting a portion of the shaft 18 near the last mentioned end, and a tubular member or stuffing box 50 having an end wall 51 which is apertured to receive the shaft 18. Encircling the shaft 18 and threaded into the open end of the chamber 50 is a gland 52. Disposed centrally in the tubular member 50 is a coil spring 53. Disposed on opposite ends of the coil spring 53 are packing rings 54 and 55. By means of this arrangement, the packing rings on opposite sides of the spring 53 are subjected to substantially equal pressure.

The recess surrounding the spring 53 is adapted to receive any of the liquid which leaks from the pipes 10 through the packing rings 54. In order to remove the liquid from the recess, there is provided an opening 56 leading into the interior of said recess and having a pipe connection to a suitable reservoir. Any leakage of liquid past the recess is prevented by the packing rings 55. 70
 75

At the opposite end of the shaft 18, each bend is provided with counter bores 57 for receiving anti-friction bearings 58. In order to prevent leakage through this end of the shaft 18, there

is provided a cap gland 59 having an outwardly extending flange 60 through which passes bolts 61 adapted to screw into the body of the bend and thereby force the cap 59 against said body. This 5 cap 59 forms a chamber 62 which may be used as a grease chamber, and is provided at the outer end with a plug 63 which permits the inspection of the end of the shaft 18 when any breakage or other disturbance takes place, and permits 10 the insertion of a rod to push out the shaft or a section thereof if the shaft breaks. Between the bend and the cap gland 59 there is provided a suitable packing washer 64 which seals the connection between the bend and the cap gland. 15 The apparatus illustrated constitutes only one embodiment of my invention, and various changes may be made without departing from the spirit of my invention or the scope thereof as defined in the appended claims.

20 Having thus described my invention, what I claim as new and desire to secure by Letters Patent is:—

1. A liquid chilling apparatus including a plurality of vertically spaced substantially horizontally extending pipes connected in series for conducting the liquid to be treated, a jacket encircling each of said pipes, an inlet header connected to certain of said jackets, a vertical return header connected to certain of said jackets, a receiver 25 connected to the outlet end of said return header below the lowermost jacket, and means for delivering volatile refrigerant to said inlet header, said means being controlled by the level of the refrigerant in said receiver.

30 2. A heat interchanger including a plurality of vertically spaced horizontal pipe sections for conducting liquid to be treated, a plurality of evaporator sections connected together in parallel and disposed respectively in heat exchange relationship with said pipe sections, means for 35 circulating volatile refrigerant through said sections, and a receiver disposed below the lowest evaporator section, and connected to the outlets of said evaporator sections.

40 3. A liquid chilling apparatus including a plurality of vertically spaced horizontal pipe sections for conducting liquid to be treated, a plurality of evaporator sections connected together in parallel and disposed respectively in heat exchange 45 relationship with said pipe sections, a receiver disposed below the lowest evaporator section and connected to the outlets of said evaporator sections, and a pump disposed below said receiver and having its suction side connected to said receiver for forcing volatile refrigerant to said evaporator sections.

45 4. A liquid chilling apparatus including a plurality of vertically spaced substantially horizontally extending pipes connected in series for conducting the liquid to be treated, a jacket encircling each of said pipes, an inlet header connected to certain of said jackets, a vertical return header connected to certain of said jackets, a surge drum 50 connected to the outlet end of said return header below the lowermost jacket, and means for delivering volatile refrigerant to said inlet header.

55 5. A liquid chilling apparatus including a plurality of vertically spaced horizontal pipes connected in series, a corresponding plurality of evaporator sections connected in parallel and disposed respectively in heat exchange relationship with said pipes, a circulating pump for forcing volatile refrigerant to said evaporator sections, 60 a liquid receiver disposed below said evaporator

sections and connected to the inlet of said pump, means for maintaining a substantially constant liquid level in said receiver, and metering devices for controlling the amount of refrigerant entering each of said evaporator sections from said 5 pump.

6. A liquid chilling apparatus including a series of horizontal substantially parallel pipes for conducting liquid to be treated, a jacket encircling each of said pipes to form therewith an 10 annular chamber for the passage of volatile refrigerant, said jackets each having an inlet of fixed flow area near one end and an outlet larger than the inlet and leading from the top of the jacket at the other end thereof, and separate 15 headers connecting said inlets and said outlets whereby said jackets are connected in parallel for the circulation of separate portions of refrigerant therethrough.

7. A liquid chilling apparatus including a plurality of vertically spaced horizontal pipes for conducting liquid to be treated, a jacket encircling each of said pipes to form an annular chamber for the passage of volatile refrigerant, an inlet near one end of each of said jackets, an 20 outlet connected to the top of each of said jackets near the other end thereof, a surge drum located below the lowermost jacket level to receive refrigerant from all of said outlets and deliver separate portions of refrigerant to each of said inlets, 30 and means for maintaining a substantially constant liquid level in said drum.

8. A liquid chilling apparatus including a plurality of horizontal substantially parallel pipes connected in series for conducting the liquid to 35 be chilled, said pipes being arranged in groups at different elevations, a jacket encircling each of said pipes, and forming a passage therewith for a volatile refrigerant, a separate inlet to an end jacket in each group, a supply pipe connected to 40 all of said inlets, an outlet connected to the other end jacket of each group and extending from the top thereof, a discharge pipe connected to all of said outlets, and connections between the 45 tops of adjoining jackets of each group for connecting said jackets of said groups in series, said supply and discharge pipes connecting the jackets of said groups in parallel.

9. A liquid chilling apparatus including a plurality of horizontal pipe sections disposed in superposed relationship for conducting the liquid to be chilled, horizontal bends connecting the pipes of each section in series in a zig-zag manner, vertical bends connecting the pipe sections in series, the top section being provided with an 50 inlet and the bottom section being provided with an outlet, whereby the liquid to be chilled travels horizontally in zig-zag fashion through each section and successively downwardly through the lower sections, a jacket encircling each of said 55 pipes to form a passage for a volatile refrigerant, couplings connecting the jackets in each section in series to form a plurality of evaporator sections, an inlet header, connections between said header and the inlets of said evaporator sections, a return header, connections between the outlets of said evaporator sections and said return header, whereby said evaporator sections are connected in parallel, a surge drum connected to the 60 outlet end of said return header and disposed 65 below the lowermost evaporator section, a circulating pump below the surge drum for pumping volatile refrigerant from the surge drum to the inlet header, and a metering device at the inlet of each of said evaporator sections for prede- 70

- termining the amount of volatile refrigerant forced into said latter sections.
10. A liquid chilling apparatus including a pipe for conducting the liquid to be treated, a jacket 5 encircling said pipe and forming therewith a passage for the delivery of a refrigerant, a shaft extending axially in the interior of said pipe, a bearing for said shaft connected to one end of said pipe, a conveyor in the interior of said pipe connected to said shaft, a cap gland connected to 10 said bearing, and a removable plug at the outer end of said cap gland to permit inspection of the shaft.
11. A liquid chilling apparatus including a series of pipes for conducting liquid to be treated, a jacket encircling each of said pipes to form a chamber for passage of refrigerant, refrigerant inlet pipes opening tangentially into certain of 15 said chambers at their lowermost portions, refrigerant outlet pipes opening from said chambers at their highest points, a receiver disposed below the lowermost of said series of pipes for receiving refrigerant from said outlet pipes, a pump for pumping refrigerant from said receiver to said 20 inlet pipes, means for maintaining a substantially constant liquid level in said receiver, and metering device for controlling the amount of refrigerant entering each of said evaporator sections 25 from said pump.
12. A liquid chilling apparatus including a series of horizontal substantially parallel pipes for conducting liquid to be treated, said pipes arranged in vertically spaced sets, a jacket encircling each of said pipes to form an annular 30 chamber for the passage of refrigerant, refrigerant inlet pipe communicating with the lowermost portion of the chamber at one side of each vertically spaced set of pipes, a refrigerant pipe communicating with the highest portion of the 35 chamber at the other side of each of said vertically spaced sets of pipes, refrigerant conducting pipes establishing communication between the chambers of each vertical set of pipes, and restrictions formed in said refrigerant inlet pipes for controlling the amount of refrigerant entering each of said chambers.

chamber at the other side of each of said vertically spaced sets of pipes, and refrigerant conducting pipes establishing communication between the chambers of each vertical set of pipes.

13. A liquid chilling apparatus including a series of horizontal substantially parallel pipes for conducting liquid to be treated, said pipes arranged in vertically spaced sets, a jacket encircling each of said pipes to form therewith an annular chamber for the passage of refrigerant, 10 refrigerant inlet pipe communicating with the lowermost portion of the chamber at one side of each vertically spaced set of pipes, a refrigerant pipe communicating with the highest portion of the chamber at the other side of each of said 15 vertically spaced set of pipes, refrigerant conducting pipes establishing communication between the chambers of each vertical set of pipes, and a receiver disposed below the lowermost of 20 said series of pipes and receiving refrigerant from said outlet pipes.

14. A liquid chilling apparatus including a series of horizontal substantially parallel pipes for conducting liquid to be treated, said pipes arranged in vertically spaced sets, a jacket encircling each of said pipes to form therewith an annular chamber for the passage of refrigerant, refrigerant inlet pipe communicating with the lowermost portion of the chamber at one side of each vertically spaced set of pipes, a refrigerant 25 pipe communicating with the highest portion of the chamber at the other side of each of said vertically spaced sets of pipes, refrigerant conducting pipes establishing communication between the chambers of each vertical set of pipes, 30 and restrictions formed in said refrigerant inlet pipes for controlling the amount of refrigerant entering each of said chambers.

NICOLAI H. HILLER.
